183,858

COMBINED FISH SCALER AND HOOK DISLODGER

Earl B. Newman, Toledo, Ohio

Application May 13, 1957, Serial No. 46,138

Term of patent 14 years

(Cl. D31—4)

FIG-1- FIG-2- FIG-3-

FIG-4- FIG-5-

Figure 1 is a front elevation of a combined fish scaler and hook dislodger showing my new design;

Figure 2 is a rear elevation thereof;

Figure 3 is a side view thereof;

Figure 4 is a top plan view; and

Figure 5 is a bottom plan view thereof.

I claim:

The ornamental design for a combined fish scaler and hook dislodger, as shown.
